[57] CLAIM

We claim the ornamental design for a portable enclosure for oxygen arc cutting equipment, as shown and described.

DESCRIPTION

FIG. 1 is a perspective view of a portable enclosure for oxygen arc cutting equipment showing our new design; FIG. 2 is a rear elevational view thereof.

FIG. 3 is a right side elevational view thereof.

FIG. 4 is a left side elevational view thereof.

FIG. 5 is a top plan view thereof;

FIG. 6 is a bottom plan view thereof.

FIG. 4
